CLAIM

The ornamental design for a home automation hub, as shown and described.

DESCRIPTION

1. Home automation hub

1.1 : Perspective

1.2 : Front

1.3 : Back

1.4 : Left

1.5 : Top

1.6 : Bottom

1.7 : Perspective, in position of use

The broken lines depict portions of the home automation hub that form no part of the claimed design.

Reproduction 1.1 is a front perspective view of the home automation hub; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof, the bottom surface being flat; and reproduction 1.7 is a perspective view thereof showing an example of the usage of the display part in operation.

1 Claim, 7 Drawing Sheets
